ATTORNEY

UNITED STATES PATENT OFFICE.

ARTURO CRISCI, OF NEW YORK, N. Y.

EGG OPENER.

Application filed September 15, 1923. Serial No. 662,878.

To all whom it may concern:

Be it known that I, ARTURO CRISCI, a citizen of the United States, and resident of the borough of Manhattan, city of New York, in the county of New York and State of New York, have invented certain new and useful Improvements in an Egg Opener, of which the following is a specification.

The object of this invention is the production of an egg-opener, by means of which the shell of an egg can be quickly and easily removed from its inner portion, by cutting said shell instead of fracturing it.

The organization of the invention comprises essentially a plurality of knives hinged to an annular disc maintained in operative position around an egg. A movable member is located above the knives and has extending therefrom projecting lugs which contact with guide edges of the knives to swing them independently of each other into and out of the path of the shell of the egg to be cut.

In the accompanying drawings Fig. 1 represents a top plan view of an exemplification of the egg opener; Fig. 2 shows a side elevation of the egg opener; Fig. 3 is a left hand side view of Fig. 2; Fig. 4 indicates a section of Fig. 1 on the line 4, 4 and Fig. 5 shows an enlarged fragmentary portion of Fig. 4.

The egg opener comprises a housing which is also its top member and is designated in its entirety by the letter A, the intermediate member designated in its entirety by the letter B, the annular bottom disc indicated in its entirety by the letter C and knives, each of which is designated in its entirety by the letter D.

The top member A comprises the annular disc portion 20 with the central opening 21. An annular outer portion 22 extends from the portion 20. A depending cylindrical wall 26 extends from the portion 22 and has formed therewith the clamping ears 27 and the supporting lug 28. A guide opening 30 is formed in the wall 26. An operating handle 32 with the depending flange 33 extends from the annular portion 22.

The intermediate member B comprises the annular portion 38 with the central opening 39, the projecting lugs 40 and the operating handle 41 with the depending flange 42. The portion of the handle 41 adjacent to the annular portion 38 is guided in the guide opening 30 of the wall 26. The annular portion

38 bears up against the annular disc portion 20 of the member A.

The annular bottom disc C comprises the annular portion 46 with the central opening 60 47 and the projection 48. The latter extends into the guide opening 30 of the wall 26.

The knives D are each loosely supported upon the bottom disc C and are hinged thereto by the thimbles 50. The knives D bear 65 between the bottom disc C and the intermediate member B. Each of the knives D has formed therewith the tooth 51 with the cutting end 52 and the guide edge 53 and the hook end 54. Each of the edges 53 70 contacts with one of the projecting lugs 40 of the intermediate member B, which in conjunction with the hook end 54 locates each knife in proper position. A spring 55 has its central portion connected to one of 75 the handles 41 and its ends 56 and 57 respectively bear against the depending flanges 33 and 42 and tends to separate the operating handles 32 and 41. The ears 27 are bent over the disc C, to hold the latter and the members A and B in place.

To use the egg-opener, it is held by the lug 28 and an egg indicated in part at 60, which is to have its shell cut is located in the openings 21, 39 and 47. The operating 85 handles 32 and 41 are then pressed toward each other against the tension of the spring 55, and the projecting lugs 40 bearing against the guide edges 53, cause the cutting ends 52 of the teeth 51 of the knives D 90 to independently project and swing into the central opening of the egg opener and cut the shell of the egg. When the operating handles are released, the cutting ends 52 are withdrawn from the egg, by the coaction of 95 the projecting lugs 40, the guide edges 53 and the hook ends 54.

Having described my invention what I desire to secure by Letters Patent and claim is:—

1. In an egg-opener the combination of an annular disc adapted to have an egg located in its opening, a plurality of knives each with a tooth hinged to said disc, a movable member in the egg opener having 100 projecting lugs, said lugs adapted to contact with the knives, and thereby simultaneously swing said knives with their teeth.

2. In an egg-opener the combination of an annular stationary disc, a plurality of 105 knives hinged to the disc, each of said knives having a guide edge and a movable inter-

mediate member having projecting lugs located over said knives, each of said lugs in the path of the guide edge of one of the knives, said disc and intermediate member adapted to have an egg extending therethrough, said knives with the movement of the intermediate member cutting the shell of said egg.

3. In an egg-opener the combination of a top member with an annular portion having a central opening, an operating handle extending from said top member, said top member having a depending cylindrical wall with clamping ears, an intermediate member having an annular portion with a central opening and having projecting lugs extending therefrom, the annular portion of the intermediate member located within the top member and bearing up against the an-

nular portion thereof, an operating handle 20 extending from the intermediate member co-acting with the other operating handle, a spring carried by one of the handles tending to separate them, an annular bottom disc within the top member and bearing up 25 against the intermediate member and a plurality of knives hinged to the disc and located in the path of the lugs of the intermediate member, said clamping ears of the top member extending over said annular disc 30 to maintain the top member, the intermediate member and bottom disc in proper relation to each other.

Signed at the borough of Manhattan, city of New York, in the county of New York and State of New York, this 29th day of August, A. D. 1923.

ARTURO CRISCI.
